HORN MOTOR AND RELAY UNIT

Robert H. Hill, Anderson, Ind., assignor to General Motors Corporation, Detroit, Mich., a corporation of Delaware

Application April 30, 1940, Serial No. 332,592

3 Claims. (Cl. 177—7)

This invention relates to automobile warning signals.

In operating simultaneously a pair of electrical horns on an automobile, it is the practice to carry the current from the battery to the two horns through a relay whose magnet coil is in circuit with the horn button. Heretofore the relay has been a unit separate from the horns.

It is an object of the present invention to construct one of the horns and the relay as a unitary structure using parts of the horn to support the relay magnet and armature and to furnish part of the magnetic circuit of the relay. As a result, the cost of manufacture and of installation of the relay is reduced.

Further objects and advantages of the present invention will be apparent from the following description, reference being had to the accompanying drawing wherein a preferred embodiment of the present invention is clearly shown.

In the drawing:

Fig. 1 is a plan view of a horn and relay unit embodying the present invention with the cover removed.

Fig. 2 is a sectional view on line 2—2 of Fig. 1.

Fig. 3 is a fragmentary side view, partly in section, looking in the direction of arrow 3 of Fig. 2.

Fig. 4 is a sectional view on line 4—4 of Fig. 2.

Fig. 5 is a wiring diagram of the circuits of the relay and two horns.

In the drawing, a collar 20 carries a projector or trumpet 21 and is fastened together with a gasket 22 and a diaphragm 23 to a base 24 by screws 25 and nuts 26 (Fig. 2). Fig. 1 shows the ends of studs 27 mounted on base 24 and receiving nuts 28 by which brackets 29 are fastened to the studs 27. Brackets 29 are fastened by rivets 31 (Fig. 2) to an E-shaped laminated magnet core 30. Core 30 receives a magnet coil 32. A rod 33 passes through the core 30 and through spacer 34, diaphragm 23, spacer 35 and cooperates with a nut 36 which clamps these parts against a shoulder 33a of the rod 33. Against a shoulder 33b of rod 33, a nut 37 clamps a spring 38, a spacer 39 and an armature 40. A nut 41 is adjustable along the rod 33.

A U or channelled frame 42 (Fig. 4) fastened to base 24 supports a stack of parts comprising (from bottom to top), the armature spring 38, insulator 43, contact bracket 44, terminal plate 45, insulator 46, terminal plate 47, circuit breaker contact blade spring 48, insulating strip 49, circuit breaker contact bracket 50. These parts are fastened by rivets 51 (Fig. 4) insulated from all parts except frame 42 and bracket 50.

Blade spring 48 carries contact 52 (extending through a hole in strip 49) engaging contact 53 on bracket 50. Nut 41 on armature rod 33 engages strip 49 to move blade spring 48 downwardly thereby to separate contact 52 from contact 53 at a certain instant during movement of armature 40 toward core 30. Contacts 52 and 53 control the circuit of magnet coil 32. Therefore the horn motor operates after the fashion of a buzzer to oscillate the diaphragm 23. A resistance 54 shunts contacts 52 and 53 to reduce sparking (Figs. 1 and 5).

The control relay forming a part of this horn motor includes a base 60 secured to horn motor base 24 and supporting a frame 61 having an upwardly extending vertical flange 62 and a downwardly extending flange 63. Flange 62 supports relay magnet center core 64 and coil 64a. Core 64 and an extension 42a of frame 42 (which is of steel) provide pole pieces of the magnetic circuit toward which an armature 65 is attracted. Armature 65 is hingedly supported on frame flange 63 by a leaf spring hinge plate 66. Armature 65 insulatingly supports a blade spring 67 carrying contact 68 for engaging a contact 69 on bracket 44.

A battery 70 is connected with terminal 71 connected by wire 72 with relay coil 64a connected by wire 73 with terminal 74 to which the horn button switch 75 is connected. A bared portion 72a of wire 72 is connected by a flexible wire 75 with blade spring 67. Contact bracket 44 is electrically connected with plate 45; and a wire 76 connects plate 45 with horn motor coil 32. A wire 77 connects coil 32 with plate 47 electrically connected with contact blade spring 48 carrying contact 52. A wire 78 connects plate 47 with spark-reducing resistance 54 which is grounded. Contact 53 is grounded through its bracket 50, rivets 51, frame 42, base 24 and automobile chassis. A clip 80 (Fig. 3) fastened to base 24 secures wires 72 and 73 against vibration.

A wire 81 connects plate 45 with the second horn motor having coil 32', contacts 52' and 53', and spark-reducing resistance 54'.

Closing the horn-button switch 75 causes relay coil 64a to be energized to effect the closing of relay contacts 68 and 69 thereby connecting the battery 70 with the magnet coils 32 and 32' of the two horns which sound as long as the switch 75 is closed.

In the combined horn motor and relay unit of the present invention, the relay has been provided at less cost than possible if the relay were a separate unit since the relay cover and one of

its contact brackets has been furnished by the horn motor. Cover 90 encloses the horn-motor and relay unit. No additional space is required since the horn-motor stack-bracket 42 houses the relay core and coil.

The cost of separately installing the relay has been eliminated.

While the embodiment of the present invention as herein disclosed, constitutes a preferred form, it is to be understood that other forms might be adopted, all coming within the scope of the claims which follow.

What is claimed is as follows:

1. A horn-motor and relay unit comprising a horn base, an electromagnet carried by the base, a U-shaped frame mounted on the base, a stack of parts mounted upon the yoke of said frame, said stack including a circuit breaker to be actuated by said electromagnet, terminal plates, insulators and a bracket carrying additional contact, a relay core and coil disposed between the sides of the frame and under the yoke, a core frame supporting the core and mounted on the

horn base, and a relay armature supported by the core frame and carrying a contact for engaging the said additional contact.

2. A unit according to claim 1 in which the yoke of the U-shaped frame provides one of the pole pieces toward which the relay armature moves.

3. A horn-motor and relay unit comprising a horn base, a hollowed frame mounted on the base, a circuit breaker mounted on the frame and having an additional contact, an armature for actuating the circuit breaker, a magnet coil for attracting the armature and having connection with said additional contact, and a relay mounted on the base for controlling the magnet coil, said relay including a center core and a coil located within the hollow of said frame, a relay armature having a contact for engaging the additional contact and a bracket secured to the base for support of the core independent of the hollowed frame.

ROBERT H. HILL.
